UNITED STATES PATENT OFFICE.

FRED C. AREY, OF OAK PARK, ILLINOIS, ASSIGNOR TO NORTHWESTERN EXPANDED METAL COMPANY, OF CHICAGO, ILLINOIS, A CORPORATION OF ILLINOIS.

MACHINE FOR EXPANDING SHEET METAL.

1,090,961.

Specification of Letters Patent. Patented Mar. 24, 1914.

Application filed October 7, 1912. Serial No. 724,298.

To all whom it may concern:

Be it known that I, FRED C. AREY, a citizen of the United States, residing at Oak Park, county of Cook, State of Illinois, have 5 invented a certain new and useful Improvement in Machines for Expanding Sheet Metal, and declare the following to be a full, clear, and exact description of the same, such as will enable others skilled in the art to 10 which it pertains to make and use the same, reference being had to the accompanying drawings, which form a part of this specification.

My invention relates to machines for expanding sheet metal and more particularly to the type disclosed in Patent 917,715 issued April 6, 1909.

It has for its object to improve the construction of such machines so as to make 20 them capable of performing their work better than heretofore, provide for convenient and accurate adjustment and insure stability.

The various features of novelty whereby 25 my invention is characterized will herein-after be pointed out with particularity in the claims; but for a full understanding of my invention and of its object and advantages, reference may be had to the following 30 detailed description taken in connection with the accompanying drawings wherein:

Figure 1 is a side elevation of a machine arranged in accordance with a preferred embodiment of my invention; Fig. 2 is an end 35 view of the machine, looking toward the left in Fig. 1; Fig. 3 is a top plan view; Fig. 4 is a view on an enlarged scale taken approximately on the plane indicated by line 4—4 of Fig. 1, the expander arms and some of the 40 gearing being omitted; Fig. 5 is a section taken approximately on line 5—5 of Fig. 4; Fig. 6 is a section taken approximately on line 6—6 of Fig. 4; Fig. 7 is a view corresponding to Fig. 2, being on an enlarged 45 scale and showing less of the machine than is illustrated in Fig. 2; Fig. 8 is a longitudinal vertical section taken just outside of the lower expander arm and illustrating the means for supporting the lower end of this 50 arm; Fig. 9 is a longitudinal vertical section through the parts shown in the lower half of Fig. 8; Fig. 10 is a plan view of the angular plate shown in Figs. 8 and 9; Fig. 11 is a section taken approximately on line 55 11—11 of Fig. 9; Fig. 12 is a vertical longi-

tudinal section through the lower end of the lower expander arm and the immediate supporting parts therefor; Fig. 13 is a view looking toward the right in Fig. 12, with the expander arm omitted; Fig. 14 is a side elevation of a portion of the supporting means for the upper end of the upper expander arm; and Fig. 15 is a view looking toward the left in Fig. 14.

The machine which I have illustrated is 65 the same as that illustrated in the patent to which I have heretofore referred except as to the means for supporting and adjusting the expander arms; my invention being concerned only with means for more rigidly 70 supporting the expander arms and permitting them to be adjusted accurately in various ways without danger that they will easily get out of place. For the sake of brevity, therefore, I shall confine the 75 detailed description, as far as possible, to my new features.

Referring to the drawings, 1 represents a suitable frame preferably comprising a long, wide base member, 2, having a wide, upright pedestal extending above the same. 4 and 5 are the two diverging expander arms above the base member of the frame and having their ends which are nearest together lying in front of the pedestal so as to receive 85 slotted sheets fed across the top of the pedestal through the usual guide, X, and expand them in the usual way. In the aforesaid patent the receiving ends of the arms are pivotally mounted and their opposite 90 ends are adjustably supported upon arms or risers projecting upwardly from the frame. The duty of machines of this kind is extremely heavy and therefore simple arms or 95 risers will not give rigidity to the expander arms but will allow them to vibrate, thus keeping down the efficiency of the machine and making it necessary to give them considerable attention to keep them in proper working order.

One of the features of my invention consists in improved supporting means which will permit the angle between the expander arms to be varied and adjusted to a nicety and which will always hold the expander arms rigid. It is also desirable to make it possible to adjust the expander arms laterally with respect to a longitudinal vertical plane, and therefore my invention also 105 contemplates a novel arrangement for se- 110

curing adjustments of this kind which will insure proper alinement in a longitudinal direction when the adjustments are made and will also insure that this alinement will be maintained during the subsequent operation of the machine. I have found that it is desirable to be able to raise and lower the receiving ends of the expander arms because it is difficult to determine in advance just how the receiving ends of the expander arms should be set and even after they have been set in the best positions for one kind of work, as to size or material, it may be better to raise or lower them somewhat for another kind of work. To illustrate: Machines of this kind are adapted to expand a slotted sheet metal strip so as to transform it into a shorter and much wider strip composed of numerous diamond-shaped cellular members. In the process of expanding, the side portions of the strip are firmly held between the chains on the expander arms and are prevented from shortening, while the central portion is being expanded and shortened. This has the effect of making the advance end of the finished strip concave and the opposite end convex, the degree of concavity and convexity depending upon conditions. I have found that by shifting the receiving ends of the expander arms from and toward each other, in the vertical directions, a change in the degree of convexity and concavity of the ends of the completed strip results, there being always some particular relative position of the receiving ends of the expander arms which will cause the expanded strip to have substantially straight ends. This is for the reason that the proportion between the length and the width of the diamond shaped cells, and the relation between these proportions in cells along the middle of the strip and those nearer the sides, varies according to the difference in vertical elevation between the receiving ends of the expander arms for any given degree of expansion of a strip in the lateral direction. Furthermore, such a relative adjustment of the expander arms increases the capacity of the machine in that it permits a wider strip to be handled than would otherwise be possible. My invention therefore contemplates also means for securing bodily vertical adjustments of the receiving ends of the expander arms in addition to the vertical adjustments at the opposite ends.

I shall first describe the means for supporting the receiving ends of the expander arms, this construction being best shown in Figs. 1 and 3 to 6 inclusive. In the arrangement shown, there is mounted on top of the pedestal, 3, an auxiliary pedestal, 6, on which is journaled one of the transverse power shafts, 7. The member 6 has depending aprons or flanges, 8 and 9, bearing

against the rear face of the main pedestal, each of these aprons or flanges being provided in the rear face with a transverse groove, 10. Resting against the flanges or aprons, 8 and 9, are flat plates, 11 and 12, respectively, each having a tongue or rib, 13, fitting slidably within the corresponding groove, 10, thus permitting these two plates to be moved laterally without changing their relations in a vertical direction with respect to the grooved members, 8 and 9. The members 11 and 12 are provided on their rear faces with vertical ribs or projections, 14. Behind and bearing against the plates 11 and 12 are brackets, 16 and 17, each having in its front face a vertical groove, 18, adapted to receive the corresponding rib or projection, 14, so that each bracket may be shifted vertically on the plate between it and the pedestal and may also be shifted laterally with the plate, the two sets of ribs and grooves arranged at right angles to each other, permitting either adjustment to be effected without regard to the other. In the arrangement shown, I have employed two sets of bolts, each of which secures together one of the brackets, the auxiliary pedestal, and the intervening plate and at the same time secures the auxiliary pedestal to the main pedestal: 20 and 21 being bolts which pass through vertically-elongated slots, 22, in the bracket, 16, through horizontally-elongated slots, 23, in the plate, 11, and through round holes in the auxiliary pedestal, the bolt, 20, passing through the flange or apron, 8, of the auxiliary pedestal and through the wall of the main pedestal, while the bolt 21 simply passes through the wall of the auxiliary pedestal at a point above the main pedestal; 100 and the bolts 24 and 25 passing through vertically-elongated slots, 26, in the bracket, 17, through horizontally-elongated slots, 27, in the plate, 12, the bolt 24 also passing through registering round holes in the apron 9 and in the rear wall of the main pedestal, while the bolt 25 simply passes through a round hole in the auxiliary pedestal.

Secured on the back of the main pedestal beneath each of the brackets 16 and 17, is a block, 28, and through each of these blocks extends a set screw, 29, which engages with the bottom edge of the overlying bracket. The plates 11 and 12 are each provided with a horizontally screw-threaded bore, 30, extending inwardly through the outer side edge thereof and into these bores extend screw-threaded shafts, 31 and 32. The shafts 31 and 32 are revolvably supported in bearings, 33, carried by the main pedestal and are provided on their outer ends with bevel gear wheels, 34, fixed thereto. The gear wheels serve as collars to prevent the shafts from moving axially in one direc- 180

tion and axial movement in the opposite direction may be prevented in any suitable way, as, for example, by providing each shaft with a collar, 35, bearing against the 5 sides of the bearing members, 33, opposite to that on which the corresponding bevel gear is located.

It will be seen that by loosening the nuts on the bolts, 20, 21, 24 and 25, the two 10 brackets may be adjusted in a vertical direction by means of the set screws, without interfering with the lateral adjustment. Similarly a lateral adjustment of either of the brackets may be obtained by turning the 15 bevel gear on the screw shaft connected with it, without interfering with the vertical adjustment.

Each of the brackets, 16 and 17, has at 20 its upper end a suitable bearing, 37, in which the supporting shaft for the receiving end of one of the expander arms is journaled, these shafts being indicated at 38 and 39, respectively, in Fig. 4. It will thus be 25 seen that by means of the set screws, 29, and the screw shafts, 31 and 32, any desired adjustment of the receiving ends of the expander arms may be effected, either being capable of being adjusted both laterally and vertically regardless of the other; 30 and, whenever an adjustment has been effected, absolute rigidity of support is obtained by simply tightening the nuts on the several bolts.

I shall now describe the means for supporting the rear end or lower end of the 35 lower expander arm, 5. On the base of the frame, just below the rear end of the lower arm lies a plate, 40, having on its under face a transverse rib, 41, which fits in a 40 transverse groove, 42, in the top of the base. Bolts, 43, pass down through laterally-elongated slots, 44, in the plate, 40, and into or through some portion of the stationary 45 base; this arrangement permitting the member 40 to be adjusted laterally of the machine without interfering with its adjustment in a longitudinal direction. The member 40 has a forwardly and downwardly inclined part, 45, which is provided on its 50 upper face with a groove, 46, which, viewed from above, extends longitudinally of the machine. On the member 45 rests a block, 47, having on its under face a rib or projection, 48, fitting into the groove, 46. The 55 block is adjustably held in place by means of bolts, 49, which pass down through the block and through slots, 50, in the member 45 elongated in directions parallel with the groove 46. On the front end of the member 45 is a set screw, 51, which engages with the front end of the block, 47, and serves to 60 adjust the block upwardly along the member 45 and to prevent it from dropping back before the nuts on the bolts 49 can be tightened. On the block, 47, is arranged a

bracket, 52, the bracket having a pair of ears, 53, lying on opposite sides of the block, and a bolt, 54, extends through these ears and through the block; the bracket being therefore mounted on the block by means 70 of a hinge. As will best be seen from Figs.

8 and 12, the bracket, 52, has an upper curved bearing seat, 55, upon which rests a curved shoe or part, 56, on the end of the expander arm, 5. The bearing seat, 55, may be provided with a groove, 57, arranged in a plane at right angles to the axis of the bolt or shaft, 54, and the member 56 may have a rib or projection, 58, adapted to fit into this groove and thus hold the end of the expander arm against lateral movement 80 on the bracket. The bracket is also provided with an arm, 59, projecting upwardly at the outer side at some distance from the expander arm and has on its upper end a journal bearing, 60, co-axial with the journal bearing, 61, in the expander arm. A power shaft, 63, extends through the journal bearing in the bracket and the bearing in the expander arm for the purpose of 85 transmitting power to the usual chains on the expander arm. On the shaft, 63, are the usual sprocket wheels, 64, and gear wheels, 65, the sprocket wheel being driven by a suitable chain, 66, passing over a 90 sprocket wheel, 67, on the power shaft, 7; and the gear wheel, 65, actuating the gear wheel, 68, in the usual way, for transmitting power to the chain in the upper half 95 of the expander arm. The expander arm 100 may be held rigidly upon the bracket by means of a bolt, 62, passing through the latter and through an elongated slot, 69, in the member 56, this bolt being loosened 105 when a vertical adjustment of the lower end of the lower expander arm is to be made.

The adjustable plate, 40, has extending into it through its outer side edge, a screw-threaded bore, 70, into which projects a screw-threaded shaft, 71, whose outer end 110 has a bearing in a bracket, 72, secured upon the base of the machine, as best seen in Figs. 1 and 2. Fixed to the shaft, 71, is a bevel gear wheel, 73; the shaft 71 and gear wheel 73 being similar to the shaft 31 and the gear 115 wheel 34 at the front end of the expander arm. On the shaft 31 is supported an arm, 74, having in its free end a journal bearing, 75. On the shaft, 71, is supported an arm or yoke, 76, having in its free end a journal bearing, 77. 78 is a shaft which extends along the side of the machine through the journal bearings 75 and 77, and is provided at its ends with bevel pinions, 79 and 80, which mesh respectively with the bevel gear, 120 34, and the bevel gear 73. Between the ends of the shaft is fixed a hand wheel, 81, by which the shaft may be turned. It will be seen that when the bolts, 43, which hold the 125 supporting plate, 40, upon the base, are 130

loosened, and the shaft, 78, is turned, the plate and the end of the expander arm carried thereby will be shifted transversely; this same movement of the shaft, 78, will 5 also turn the gear wheel, 34, producing an adjustment of the front end of the expander arm, 5. It will thus be seen that by properly proportioning the parts, the entire lower expander arm may be moved in or 10 out relative to the central longitudinal axis of the machine without changing the angle of any of its parts with respect to such longitudinal axis. In other words, any line on the expander arm which is at one time 15 parallel with a vertical plane containing the longitudinal axis of the machine always remains parallel to that plane regardless of its distance therefrom. This arrangement permits the expander arm to be adjusted 20 transversely, quickly and conveniently with the assurance that the alignment in the longitudinal direction will always be correct and it also insures that neither end of the expander arm can shift laterally with- 25 out a corresponding movement on the part of the other arm. It will also be seen that by shifting the supporting block, 47, on the member 43, the outer end of the lower expander arm may be raised or lowered so as 30 to vary the degree of divergence between the two expander arms.

The means for supporting the rear end of the upper expander arm, 4, is best illustrated in Figs. 2, 7, 14 and 15. Referring 35 to these figures, 85 is a plate formed on or secured on top of the base of the machine below the rear end of the upper expander arm. In the upper surface of this plate is a transverse groove, 86. On the plate rests 40 a bracket, 87, having an elongated rib or projection, 88, fitting into the groove, 86. The bracket is secured in place by means of bolts, 89, which pass down through laterally-elongated slots, 90, in the bracket, 45 through the plate, 85, and into or through a part of the base. Secured on the front face of the bracket by means of bolts, 91, passing through vertically-elongated slots, 92, in the bracket is a member, 93. The 50 bracket and the member 93 are provided with forwardly-projecting ears, 94 and 95, respectively, lying one below the other and a set screw, 96, passing through the ear, 94, and engaging with the under side of the 55 ear 95, serves to move the member 93 up or permit it to drop down when the bolts, 91, are loosened. The member 93 may therefore be adjusted in a vertical direction on the bracket and may be adjusted laterally 60 with the bracket. The rear end of the upper expander arm is secured to an overlying part, 101, of a heavy rigid upright member, 100; the lower end of the upright member being provided with downwardly-projecting 65 ears, 102, which lie at opposite sides of

the member, 93, and are secured thereto by means of a heavy bolt, 103, passing through the ears and the member, 93; the member 93 being made comparatively wide so that the heavy upright is rigidly supported except in 70 so far as angular movements around the axis of the heavy bolt 103 are concerned. The overhanging part, 101, of the upright is preferably provided on its under side with a concave seat, 104, into which fits a 75 convex part, 105, at the upper rear corner of the upper expander arm; the expander arm being held securely in the seat by means of bolts, 106, passing down through elongated slots, 107 into the expander arm. Lateral movement of the expander arm on the upright may be effectively prevented by providing a tongue and groove connection, 108, between the same; the tongue and groove extending at right angles to the axis of curvature of the bearing surface between the upright and the expander arm; this axis of curvature corresponding with the axis of the power shaft, 109, which drives the usual chain in the upper half of this expander 80 arm and consequently this power shaft may conveniently be journaled in a comparatively long bearing, 110, in the upright. By supporting one end of the power shaft in the upright, further rigidity is given to the 85 upper expander arm, so that it will remain firm and rigid during the operation of the machine. On the shaft, 109, are the usual sprocket wheel, 110, by means of which it is rotated, and the gear wheel, 111, which meshes with the usual gear wheel, 112, for driving the chain in the lower half of the 90 expander arm.

The bracket, 87, is provided with a screw-threaded bore, 115, extending laterally into the same through its outer side edge and into this bore extends a shaft, 116, carrying a bevel gear wheel, 117, the outer end of the shaft being supported in a stationary bracket, 118. The parts, 116 to 118 may be 105 identical with the parts 71 to 73 and therefore require no further explanation. On the shaft 116 is an arm or yoke, 119, similar to the arm or yoke, 76, on the shaft 71. Similarly, on the shaft 32 which serves to adjust 110 the front end of the upper expander arm in a transverse direction is an arm, 120, corresponding to the arm 79 on the opposite side of the machine. 121 represents a shaft extending lengthwise of the machine and journaled in the members 119 and 120 and having at its ends bevel pinions meshing with the bevel gear wheels 34 and 117. The shaft 121 may also be provided with a hand 115 wheel, 122, by which it may be turned. It will thus be seen that by loosening the bolts, 89, at the rear end of the expander arm, and the bolts, 24 and 25, at the front end, the upper expander arm as a whole may be adjusted in and out relative to the longitudi- 120 125 130

nal axis of the machine, by simply turning the hand wheel 122; the adjustments being exactly the same as the corresponding adjustments of the other arm which I have heretofore explained. After the desired adjustments have been effected, the bolts 89, 24 and 25 are again tightened and the expander arm is rigidly locked in position. When it is desired to raise or lower the rear end of the upper expander arm, the bolts 91 are loosened and the set screw 96 is turned in the proper direction so as to raise or lower the supporting member 93. Since this adjustment changes the angular relation between the upright and the upper expander arm, the fastening bolts, 106, between the upright should be loosened at the time this adjustment is made and should again be tightened after the adjustment is complete.

20 While I have illustrated and described only a single preferred embodiment of my invention, I do not desire to be limited to the exact structural details thus illustrated and described; but intend to cover all forms 25 and arrangements which come within the terms employed in the definitions of my invention constituting the appended claims.

I claim:

1. In a machine of the character described, 30 a guide for sheets to be expanded, expander arms diverging from a point adjacent to the delivery end of the guide, and means for bodily adjusting the expander arms at the ends adjacent to the guide transversely to 35 the plane of a sheet in the guide.
2. In a machine of the character described, expander arms arranged on opposite sides of a horizontal plane and diverging from one end toward the other, and means for adjusting the ends of the arms nearest each other transversely of said plane.
3. In a machine of the character described, expander arms arranged on opposite sides of a vertical plane and diverging from each other on opposite sides of a horizontal plane, and means for simultaneously adjusting both ends of one of said arms relative to said vertical plane.
4. In a machine of the character described, 50 expander arms arranged on opposite sides of a vertical plane and diverging from each other on opposite sides of a horizontal plane, and means for simultaneously adjusting both ends of either of said arms relative to said vertical plane.
5. In a machine of the character described, expander arms arranged on opposite sides of a vertical plane and diverging from each other on opposite sides of a horizontal plane, 60 and means for adjusting both ends of each of said arms bodily in directions transverse to each of said planes.
6. In a machine of the character described, expander arms diverging from each other 65 on opposite sides of a horizontal plane, and

means for adjusting either end of either of said arms bodily from and toward said plane.

7. In a machine of the character described, expander arms diverging from each other 70 on opposite sides of a horizontal plane, means for adjusting either end of either of said arms in directions transverse to said horizontal planes and means for simultaneously adjusting both ends of either of said 75 arms transversely to a vertical plane.

8. In a machine of the character described, a frame, diverging expander arms, a member mounted on the frame at each end of each of said expander arms in such a manner as to be adjustable bodily in two directions at right angles to each other, and connections between said expander arms and said members to permit relative angular movements between the same about horizontal-axes.

9. In a machine of the character described, a frame, diverging expander arms, a member mounted on said frame at each end of each of said expander arms so as to be adjustable laterally in a horizontal direction and in a direction transverse to said horizontal direction, means for supporting the ends of the expander arms on the adjacent members, and an operating mechanism 95 between the two members supporting each expander arm for permitting them to be adjusted simultaneously in said horizontal direction.

10. In a machine of the character described, 100 a frame, vertically-diverging expander arms above the frame, means for supporting on the frame the ends of the arms nearest each other, a connection between the frame and the remaining end of the 105 lower arm, a bracket on the frame, an upright extending from the bracket and projecting laterally across the top of the remaining end of the upper arm, and means for rigidly securing the upper arm to the 110 overlying portion of said upright.

11. In a machine of the character described, a frame, vertically-diverging expander arms above the frame, means for pivotally supporting on the frame the ends 115 of the arms nearest each other, an adjustable connection between the frame and the remaining end of the lower arm, a bracket on the frame beneath the upper arm, a part vertically-adjustable on said bracket, an upright hinged to said part and extending upward in proximity to the upper end of the upper arm, and means for rigidly securing the upper arm to the adjacent portion of said upright.

12. In a machine of the character described, 125 a frame, vertically-diverging expander arms above the frame, means for pivotally supporting on the frame the ends of the arms nearest each other, an adjust-

- able connection between the frame and the remaining end of the lower arm, a bracket on the frame beneath the upper arm, a part vertically-adjustable on said bracket, an upright hinged to said part and having a part projecting laterally above the remaining end of the upper arm, and means for rigidly securing the upper arm to the overlying portion of the upright.
- 10 13. In a machine of the character described, a frame, vertically-diverging expander arms above the frame, means for pivotally supporting on the frame the ends of the arms nearest each other, an adjustable connection between the frame and the remaining end of the lower arm, a bracket on the frame beneath the upper arm, a part vertically-adjustable on said bracket, an upright connected to said part by means of a long hinge and extending upward in proximity to the upper end of the upper arm, and means for rigidly securing the upper arm to the adjacent portion of said upright.
- 15 14. In a machine of the character described, a frame, vertically-diverging expander arms above the frame, means for pivotally supporting on the frame the ends of the arms nearest each other, an adjustable connection between the frame and the remaining end of the lower arm, a bracket on the frame beneath the upper arm, said bracket having a wide vertically-adjustable part, an upright having on its lower end ears lying on opposite sides of a member projecting laterally above the remaining end of the upper arm, means for rigidly securing the upper arm to the overlying portion of the upright, and a bolt passing through said ears and said part.
- 20 15. In a machine of the character described, a frame, diverging expander arms, a member mounted on said frame at each end of each of said expander arms so as to be adjustable laterally in a horizontal direction, means for supporting the ends of the expander arms on the adjacent members, a screw shaft between each of said members and the frame, and mechanism between the two shafts connected with the members supporting each expander arm for simultaneously turning the shafts associated with either arm so as to adjust either arm bodily.
- 25 16. In a machine of the character described, a frame, diverging expander arms above the frame, supporting brackets for the ends of each of said arms, each supporting bracket having a wide bearing surface on the frame, and means for adjusting said brackets on the frame.
- 30 17. In a machine of the character described, a frame, vertically-diverging expander arms above the frame, means for supporting the ends of the arms nearest each other on the frame, a connection between the frame and the remaining end of the lower arm, a bracket having a wide bearing surface on the frame, means for adjusting said bracket laterally along the frame, and a heavy upright extending upwardly from the bracket and rigidly secured at its upper end to the remaining end of the upper arm.
- 35 18. In a machine of the character described, a frame, vertically-diverging expander arms above the frame, means for pivotally supporting on the frame the ends of the arms nearest each other, an adjustable connection between the frame and the remaining end of the lower arm, a bracket on the frame below the upper end of the upper arm, a part vertically adjustable on said bracket, an upright hinged to said part and extending in proximity to the upper end of the upper arm, said upright having a broad transverse bearing surface, and means for rigidly holding the upper end of the upper arm against said bearing surface.
- 40 19. In a machine of the character described, a frame, vertically-diverging expander arms above the frame, means for supporting on the frame the ends of the arms nearest each other, a connection between the frame and the remaining end of the lower arm, an upright extending from the upper end of the upper arm into proximity to said frame, said upright having a long base measured in a direction transverse to the frame, means for connecting said base to the frame, means for rigidly connecting the upper end of the upright to the adjacent end of the upper arm, said upright being in the form of a deep beam having its greater cross dimension extending transversely of the frame.
- 45 20. In testimony whereof, I sign this specification in the presence of two witnesses.
- 50 FRED C. AREY.
